PLASTIC SHEET MATERIAL

David Lyon, New Britain, Conn., assignor to Rowland Products, Inc., Kensington, Conn., a corporation of Connecticut

Filed Apr. 13, 1964, Ser. No. 79,478

Term of patent 14 years

(Cl. D87—3)

FIG. 1

FIG. 2

FIG. 3

FIGURE 1 is a front plan view of a full width of plastic sheet material showing my new design, the ornamental pattern being shown in full lines with variation in intensity of color in the differentially colored central band being indicated by intensity of stippling which color intensity is substantially uniform along the length of the sheet material. The ornamental design motif is formed in the central band below the surface thereof and repeats along the length of the sheet material between each vertical dash mark;

FIGURE 2 is a rear view of the plastic sheet material of FIGURE 1, the center of the pattern being obscured by the intensity of color in the center of the sheet material. FIGURE 2 is shown broken away for convenience of illustration; and

FIGURE 3 is an edge view of the sheet material showing the band of color by stippling.

I claim:

The ornamental design for plastic sheet material, as shown and described.
